(57) **CLAIM**

The ornamental design for an electronic gaming machine star-shaped wheel topper display housing, as shown and described.

DESCRIPTION

FIG. 1 is a perspective view of a first embodiment of an electronic gaming machine wheel topper, showing our new design;

FIG. 2 is a perspective view thereof;

FIG. 3 is a front elevational view thereof;

FIG. 4 is a rear elevational view thereof;

FIG. 5 is a top plan view thereof;

FIG. 6 is a bottom plan view of;

FIG. 7 is a right side view thereof;

FIG. 8 is a left side view thereof;

FIG. 9 is a perspective view of a second embodiment of an electronic gaming machine wheel topper, showing our new design;

FIG. 10 is a perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a right side view thereof; and,

FIG. 16 is a left side view of.

In the drawings, the broken lines depict environmental subject matter only and form no part of the claimed design.

1 Claim, 8 Drawing Sheets
